(57) CLAIM

The ornamental design for a martial arts shoe, as shown and described.

DESCRIPTION

FIG. 1 is a top perspective view of a martial arts shoe showing my new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a back view thereof.

The broken line showing of the sole in the Figures is for illustrative purposes only and forms no part of the claimed design.
